INSTRUMENT SUPPORTING STAND

Raymond Mooney, Kenilworth, Ill., assignor to
 Quick-Set, Incorporated, Chicago, Ill., a corpora-
 tion of Illinois

Application January 30, 1947, Serial No. 725,251

14 Claims. (Cl. 248—178)

1

This invention relates to an adjustable supporting stand for cameras and like instruments and more particularly to a supporting stand having an instrument supporting platform which may be raised or lowered without the necessity of adjusting the position or length of the supporting legs.

In supporting stands of this character it is desirable to have a maximum amount of flexibility in the possible positioning of the supported instrument with only a minimum amount of adjustment being required. Some flexibility has previously been obtained in connection with the possible positioning of the instrument supporting platform in such supporting stands by utilizing a swivel mounting such as that disclosed in applicant's Patent No. 2,143,606, issued January 10, 1939. Such a construction provides for a single control member adapted to adjust the position of the platform, the latter being pivotally and rotatably mounted in relation to a base member supported by extensible legs.

However, although the platform is so mounted and has some flexibility as to possible positioning, changing the height at which the platform is supported requires a considerable amount of adjustment of the whole supporting stand, since it is usually necessary to adjust all of the extensible legs to raise or lower the platform.

It is therefore an object of this invention to provide a supporting stand for cameras and the like which not only provides a maximum amount of flexibility in the possible azimuth and angle of elevation of the supported instrument, with a minimum amount of adjustment, but also provides for an equally simple adjustment of the height of the instrument when desired.

It is also an object of this invention to provide a supporting stand of the character described which has control members for adjusting the azimuth, angle of elevation and height of the instrument, disposed adjacent to the supported instrument where they are easily accessible during the actual operation of the instrument.

It is a further object of this invention to provide a supporting stand of the character described in which control members for adjusting the azimuth, angle of elevation and height of the instrument are disposed in relation to each other and to the supporting legs so that they are readily accessible with a minimum amount of interference from adjacent parts.

Another object of this invention is to provide a supporting stand of the character described which is capable of being folded compactly when

2

not in use, with all control members locked in a substantially unprotruding position.

Another object is to provide a supporting stand of the character described which has means for making large adjustments in height, as well as means, operable after the large adjustment has been made, for making smaller adjustments.

Another object is to provide a supporting stand which because of its unique construction may be set up for use, with the supported instrument properly positioned, more rapidly than conventional types of such supporting stands.

Another object is to provide a supporting stand having a longitudinally movable shaft supporting the instrument supporting platform, which shaft may be moved to any desired position by a manually operated crank member, and secured in that position by a manually operated brake member.

Another object is to provide a novel braking member for the movable shaft carrying the instrument supporting platform which is adapted to lock the shaft against further movement when the instrument has been adjusted to the desired height.

Further objects, features, capabilities and advantages are comprehended by the invention, as will become evident as the description proceeds and from an examination of the accompanying drawings which illustrate one embodiment of the invention and in which similar numerals refer to similar parts throughout the several views.

In the drawings:

Figure 1 is a side elevation of a tripod embodying the invention.

Figure 2 is an enlarged fragmentary view from above of the base member of the tripod and associated parts.

Figure 3 is an enlarged fragmentary side elevation shown partly in vertical cross-section of the base member of the tripod and associated parts, taken substantially in the plane of the line 3—3 of Figure 2.

Figure 4 is an enlarged fragmentary side elevation shown partly in vertical cross-section of the base member of the tripod and associated parts taken substantially in the plane of the line of 4—4 of Figure 2.

Figure 5 is an enlarged fragmentary side elevation of the upper portion of the tripod, the tripod being shown in position for use.

Figure 6 is an enlarged fragmentary side elevation of the upper portion of the tripod, the parts being shown in fully collapsed position.

Figure 7 is an enlarged fragmentary view from

above the base member and associated parts of a modified form of tripod embodying the invention.

Figure 8 is an enlarged fragmentary elevation shown partly in vertical cross-section of the base member and associated parts shown in Figure 7, taken substantially along the line 8-8 of Figure 7.

Referring now to Figure 1, which illustrates a tripod embodying one form of the invention shown in position for use with a camera or like instrument, the extensible legs 10 are locked in an extended position and spread to form a firm support for the triradial base member 12. As shown in the remaining figures, the legs 10 are each pivotally secured to an arm of the base member 12. These arms have a vertical cross-section of inverted U-shape and the upper end of each leg is pivotally secured within the depending sides of one of the arms by the bolt 14. The depending lugs 16 on the lower surface of each arm act as stop means to limit the outward swing of the legs 10.

As shown in Figs. 2, 3 and 4, the sleeve 18 is mounted in the central opening 20 in the base member 12, the flange 22 on the sleeve 18 being secured to the base member 12 by the securing means 24. Inserted within the sleeve 18 and supported thereby is the shaft 26. The projecting pin 28 extends inwardly from the inner wall of the sleeve into the longitudinal groove 30 in the shaft 26. The shaft 26 may thus be moved longitudinally, but the pin 28 will prevent the shaft from rotating. The shaft 26 also has the longitudinal rack 32 formed on its outer surface with which the pinion 34 is adapted to cooperate. The pinion 34 is carried by the shaft 36 which is journaled in the projecting arms 38 and 39 formed as extensions of the upper end of the wall of the sleeve 18 immediately above the flange 22, an opening being formed in the sleeve between said arms. The shaft 36 is so positioned with respect to said opening that the teeth 40 of the pinion 34 are disposed slightly within the inner circumference of the sleeve, and the shaft 26 is so aligned with respect to the sleeve that the teeth of the rack 32 will normally mesh with the teeth 40 of the pinion 34. One end of the shaft 36 extends outwardly from the sleeve 18 at a point substantially midway between two of the arms of the base member 12. The crank member 44 is pivotally secured within an axially aligned transverse slot 46 in the outer end 42 of the shaft 36. The threaded sleeve 48 which is carried by the crank member 44 is adapted to be threaded upon the threaded outer end 42 of the shaft 36 to form a rigid joint between the crank member 44 and the shaft 36 when so desired. When the sleeve 48 is so positioned on the shaft 36 the crank member 44 may be manually rotated by utilizing the rotatable handle member 50. Rotation of the crank member 44 is transmitted to the shaft 36 and the pinion 34, and the rotation of the pinion 34, in turn, will cause the shaft 26 to be moved up or down, depending upon the direction of rotation of the crank member 44.

The shaft 26 has the shoulder 52 adjacent its upper end as shown in Figure 5, and the resilient washer 54 is mounted on the shaft 26 adjacent the shoulder 52. When the shaft 26 is moved sufficiently in a downward direction, the washer 54 will bear against the cap 56 which is adapted to form a protective cover for the top of the sleeve 18 and the pinion 34 and will thus serve

to limit the downward movement of the shaft. The opposite end of the shaft 26 is threaded to receive a stop means in the form of a removable collar 58, which when threaded thereon operates to limit the upward movement of the shaft 26 by bearing against the lower end 60 of the sleeve 18 when the shaft is moved sufficiently in an upward direction. Any other suitable form of removable stop means could be utilized, of course. The platform 62 is pivotally and rotatably secured to the upper end of the shaft 26 in a manner disclosed in applicant's Patent No. 2,143,606, issued January 10, 1939. This type of swivel mounting of the platform enables it to be moved to and secured in any desired position by operation of the control member 64 which extends outwardly therefrom. The instrument to be supported is secured to the platform by the set screw 66 which projects through the platform and which may be operated by rotating the milled wheel 68.

As shown in Figure 3, the sleeve 18 has a longitudinal slot 70 formed therein, which is adapted to receive the brake shoe 72. The length of the slot at the outer surface of the sleeve is greater than the length of the slot at the inner surface of the sleeve. This characteristic may readily be obtained by forming the slot with a circular cutter, so that the end walls of the slot are short arcs of a common circle, and the edges of the slot are chords of that common circle.

The length of the brake shoe 72 is greater than the length of the slot at the inner surface of the sleeve, but shorter than the length of the slot at the outer surface of the sleeve. In addition, the ends of the brake shoe adjacent the inner face of the shoe are beveled to permit the shoe to be moved inwardly in the slot 70 a distance sufficient to cause the inner face of the shoe to project inwardly from the inner surface of the sleeve 18 and to bear against the shaft 26, the inner face of the shoe being suitably curved to fit the shaft so that the effective frictional surface of the shoe is increased. The main body of the shoe, however, is too long to permit it to pass through the inner side of the slot 70 so that the shoe cannot fall through the slot if the shaft 26 is withdrawn from the sleeve 18.

The spring member 74 abuts the brake shoe 72 at both ends and normally has a convex disposition with respect to the adjacent side of the brake shoe. The thumb screw 76 is adapted to be moved inwardly or outwardly in the threaded opening 78 in the base member 12, which opening is so aligned with the slot 70 that the reduced portion 80 of the inner end of the thumb screw is adapted to extend through the centrally located opening 82 in the spring member 74 and to be received by the recess 84 in the outer face of the brake shoe 72. The slot 70 in the sleeve 18 and the opening 78 in the base 12 are also so disposed that the thumb screw 76 will be centrally located between two of the arms of the base 12 at a point opposite the pinion 34, which permits the operator to have ready access to the thumb screw with one hand while operating the crank member 44 with the other hand.

The thumb screw 76 has the stop pin 77 secured therein adjacent the shoulder 86. This pin will act as a stop to limit the possible outward movement of the thumb screw so that the various components of the brake mechanism cannot be sufficiently displaced to make the mechanism inoperative.

When the thumb screw 76 is tightened, the

shoulder 86 adjacent the reduced portion 80 will bear against the spring member 74. As the thumb screw 76 is moved inwardly the pressure exerted by the shoulder 86 on the spring member 74 will tend to compress the latter, increasing the pressure on the brake shoe 72, which will in turn exert a gradually increasing pressure on the shaft 26. As the screw 76 is moved farther inward, the reduced portion 80 will move farther into the recess 84 in the outer surface of the brake shoe 72 and will eventually bear against the base of this recess. Any further inward movement of the screw 76 will then be transmitted directly to the brake shoe 72 without further compressing the spring member 74.

This arrangement permits only a predetermined amount of compression of the spring member 74, which amount is well below the elastic limit of the spring. The possibility of breaking or permanently deforming the spring is therefore substantially eliminated. In addition, it may be desirable at times to apply substantially more braking force than can be exerted by the compression of the spring member within the limit described, and the direct transfer of pressure from the end 80 of the thumb screw 76 to the brake shoe 72 may then be utilized.

The braking mechanism may therefore be easily adjusted to exert a moderate amount of pressure over a rather wide range, or a much heavier pressure when desired. This is particularly advantageous since the moderate pressure adjustment may be used to create sufficient friction to counterbalance the weight of the instrument when it is placed on the supporting platform. By proper adjustment of the brake mechanism within this moderate pressure range it will be found possible to find a point where the instrument may be moved up and down by rotating the crank, but will remain in the adjusted position when there is no pressure applied to the crank. This is a very convenient method of handling height adjustments up until the time when all other adjustments have been made and it is desired to secure the position of a camera, for instance, until the photograph has been taken.

For this securing operation a much larger pressure is needed than can be obtained from compression of a spring, which would have the lighter pressure and range of adjustment desirable for maintaining the counterbalance effect as previously described. Consequently the direct transfer of pressure to the brake shoe that occurs when the thumb screw is moved inwardly a predetermined distance is designed to produce this larger pressure. By this means it is possible to lock the shaft to support a weight much greater than that of any instrument which might be placed on the supporting platform, and at the same time to eliminate all possibility of side motions of the shaft in relation to the sleeve, which stability is of primary importance when working with a camera or like instrument.

As mentioned above, the collar 58 or other stop means normally secured to one end of the shaft 26 may be removed when desired. The shaft 26 may then be drawn out of the sleeve 18. This feature provides an additional advantage in that the shaft 26 may be inverted from the previously described position and reinserted into the sleeve 18 in the opposite direction so that the platform 62 is at the lower, rather than the upper end. The collar 58 may then be threaded back onto what is now the upper end of the shaft 26 and the position of the platform relative to the base 12

may be adjusted in the same manner as previously described. The possible positioning of the supported instrument is thus not restricted by the unextended length of the extensible legs 10. By such adjustment the instrument may be supported substantially at the level of the surface supporting the legs, if desired.

As shown in Figure 6, when the shaft 26 is moved in a downward direction until the resilient washer 54 abuts the cap 56, the shaft 36 and the crank member 44 are left in such a position that the sleeve member 48 may be loosened and drawn back on the crank member 44, and the latter may then be folded back adjacent the cap 56 between the platform 62 and the base 12. The control member 64 may then be adjusted so that it overlies the crank member 44 and extends downwardly substantially parallel to the shaft 26 between the two arms of the base member 12 which do not have the thumb screw 76 or the shaft 36 disposed therebetween. The control member 64 may be secured in this position since it operates to clamp the platform 62 in any desired position at will. This folding of the crank member 44 and the depressing and locking of the control member 64 provides a convenient method of collapsing the supporting stand when not in use. As shown in Figure 6, the extensible leg members 10 may also be folded inwardly so that they are substantially parallel to the shaft 26.

In order to facilitate returning the pinion and rack to their proper relative position after the shaft 26 has been removed from the sleeve 18, so that the crank 44 will be properly disposed for folding as described, the effective number of teeth 35 in the rack 32 may be made a whole multiple of the number of teeth in the pinion 34. Consequently, if, when the shaft 26 is being inserted in the sleeve 18 from above, the crank 44 is held in the position required for proper folding and the 40 rack 34 is meshed initially with the pinion 32 while the crank is in that position; then, after moving the shaft to its lowermost position with the required whole number of turns of the crank, the latter will automatically be disposed in the 45 original starting position. The possibility of having to make several attempts at obtaining the proper relative positions between the rack and pinion is therefore substantially eliminated.

As mentioned above, the thumb screw 76 and the shaft 36 are centrally located between two adjacent pairs of the arms of the base member 12. This enables the supporting stand to be set up so that the arm of the base member 12 between the thumb screw 76 and the protruding end 42 of the shaft 36 extends in the direction in which the camera or the like instrument is pointed. The thumb screw 76 and the crank member 44 are then in a conveniently accessible position during the operation of the supported instrument and the disposition of the legs 10 is such that they will not interfere with the free movement of the operator.

The steps in setting up the supporting stand from the collapsed position in which it will normally be carried will usually be as follows: The operator will release the control member 64 from its depressed position and will rotate the thumb screw 76 in the proper direction to release the 65 brake shoe 72 and provide for the free movement of the shaft 26. He will then unfold the crank member 44 and thread the sleeve 48 onto the shaft 36 and rotate the crank member 44 until the shaft 26 has reached a position substantially in the midpoint of its possible travel.

The shaft may then be locked in this position by tightening the thumb screw 76 and the legs 10 may be unfolded and extended to approximately the desired height. After placing the supporting stand securely on its legs 10 and securing the camera or other instrument to the platform 62 with the set screw 66, the thumb screw 76 may then again be loosened and the exact height desired attained by rotating the crank member 44 in the appropriate direction. All of this may be done quite rapidly, which is a decided advantage, particularly in photographic work, and any minor corrections which are found to be desirable later on may be easily made by operating the set screw 76 and the crank member 44 simultaneously, without disrupting the adjustment of the other portions of the supporting stand.

It is thus apparent that a rough setting of the height of the supporting stand may be made initially, and subsequent changes within the limits of the length of the shaft 26 may be made without resorting to adjustments in the length of the legs 10. At the same time these later adjustments may be made without the necessity of interrupting the operation of the instrument substantially, since the hands of the operator need be moved only a very short distance to accomplish such adjustments.

Another possible embodiment of the invention is that shown in Figures 7 and 8. The relative position of the two control members is somewhat different in that the pinion 34 is disposed directly above the brake mechanism. The brake shoe 88 is provided with a flat rather than a concave inner face, since the shoe now bears against the flat teeth of the rack 32, rather than the convex surface of the shaft 26. This arrangement permits the elimination of the pin 28 and the groove 30 previously provided to maintain the shaft 26 in proper alignment. The two abutting flat faces of the brake shoe 88 and the rack 32 now provide for sufficient alignment without any additional means.

In addition, this embodiment has the coil spring 90 in place of the arcuate spring 74, but the function of the coil spring is identical with that of the arcuate spring member. The washer 92 is inserted between the shoulder 86 on the thumb screw 76 and the spring 90 to provide an enlarged bearing surface for the outer end of said spring.

This disposition of the two control members in this modification is such that the operation may conveniently stand between the legs between which the thumb screw is disposed and have ready access to both the thumb screw 76 and the crank member 44, the advantages of which have been fully explained above. It is obvious, of course, that the shaft 36 and the pinion 34 could be disposed so that the crank member 44 would extend out from the sleeve 94 in the opposite direction if such an arrangement would be more desirable.

In the foregoing description of the illustrative embodiments of this invention, reference has been made to the sleeves 18 and 94 being located centrally of the base member 12. It is to be understood, however, that the sleeves need not be disposed centrally of the base member, although such central disposition will generally be preferred. In other words, the utility of the invention can be fully realized in certain constructions where the sleeve member is located eccentrically to the base member. Furthermore, the invention contemplates constructions wherein the sleeve 18 or 94 and the base member 12 are made as a

single unitary piece rather than as two pieces assembled in the manner here illustrated.

The drawings and the above discussion are not intended to represent the only forms of this invention which are possible, in regard to details of the construction. Changes in form and in the proportion of parts, as well as the substitution of equivalents are contemplated, as circumstances may suggest or render expedient, without departing from the spirit or scope of this invention.

What is claimed is:

1. A supporting stand for cameras and the like comprising a base, a plurality of legs adapted to support said base, a support shaft mounted for 15 slidable movement through said base, one end of said support shaft being adapted to support a platform, a longitudinal rack on said support shaft, a pinion carried by a pinion shaft rotatably supported by said base, said pinion being disposed to engage said rack, a crank member pivotally connected to one end of said pinion shaft, means for locking the pivotal connection between said crank member and said pinion shaft at will so that said crank member becomes fixed with respect to said 20 pinion shaft and is adapted to rotate said pinion for causing said support shaft to move longitudinally with respect to said base, stop means establishing at least one limit of longitudinal movement of said support shaft, the length of said rack and the diameter of said pinion being such that 25 said pinion and said rack may be initially brought into an engaging relationship of such a character that when said support shaft is moved so that said end of said support shaft adapted to support a platform is brought into close relation to said base and further movement in that direction is prevented by said stop means, said crank member will be disposed so that when said locking means is released from said pivotal connection between 30 said crank member and said pinion shaft and said crank member is pivoted toward said upper end of said support shaft, said crank member will fold adjacent said support shaft in close association with said base, so that it is substantially within 35 the general outline of that end of said supporting stand, and adjustable brake means adapted to be caused to exert frictional pressure of selected amounts on said support shaft at will.

2. A supporting stand for cameras and the like comprising a multiradial base, a supporting leg pivotally secured to each arm of said base, a support shaft adapted to be inserted in said base for 40 slidable movement through said base, one end of said support shaft being adapted to support a platform, a longitudinal rack on said support shaft, a pinion carried by a pinion shaft rotatably supported by said base, said pinion being disposed to engage said rack, a crank member pivotally connected to one end of said pinion shaft, means for locking the pivotal connection between 45 said crank member and said pinion shaft at will so that said crank member becomes fixed with respect to said pinion shaft and is adapted to rotate said pinion for causing said support shaft to move longitudinally with respect to said base, stop means establishing at least one limit of longitudinal movement of said support shaft, the length of said rack and the diameter of said rack and the diameter of said pinion being such that 50 said pinion and said rack may be initially brought into an engaging relationship of such a character that when said support shaft is moved so that said end on said support shaft supporting said platform is brought into close relation to said base and further movement in that direc-

tion is prevented by said stop means, said crank member will be disposed so that when said locking means is released from said pivotal connection between said crank member and said pinion shaft, and said crank member is pivoted toward said end of said support shaft, said crank member will fold adjacent to said support shaft in close association with said base, so that it is substantially within the general outline of that end of said supporting stand, said pinion shaft being so disposed in relation to said base that the end of said pinion shaft to which said crank member is pivotally attached extends outwardly from said base in a vertical plane disposed between one pair of said arms of said base, adjustable brake means adapted to be caused to exert frictional pressure of selected amounts on said support shaft at will against longitudinal movement, and an operating member adapted to control the operation of said brake means, said brake means and said operating member being so disposed in relation to said base that said operating member extends outwardly from said base in a vertical plane disposed between a second pair of said arms of said base.

3. A supporting stand for cameras and the like comprising a multiradial base, a supporting leg pivotally secured to each arm of said base, a support shaft adapted to be inserted for sliding movement through said base, a platform mounted on one end of said support shaft, a handle member extending from said platform and adapted to control the position of said platform relative to said support shaft, a longitudinal rack on said support shaft, a pinion carried by a pinion shaft rotatably supported by said base, said pinion being disposed to engage said rack, a crank member pivotally connected to one end of said pinion shaft, means for locking the pivotal connection between said crank member and said pinion shaft at will so that said crank member becomes fixed with respect to said pinion shaft and is adapted to rotate said pinion for causing said support shaft to move longitudinally with respect to said base, stop means establishing at least one limit of longitudinal movement of said support shaft, length of said rack and the diameter of said pinion being such that said pinion and said rack may be initially brought into an engaging relationship of such a character that when said support shaft is moved so that said platform is brought into close relation to said base and further movement in that direction is prevented by said stop means, said crank member will be disposed so that when said locking means is released from said pivotal connection between said crank member and said pinion shaft, and said crank member is pivoted toward said end of said support shaft, said crank member will fold adjacent to said support shaft in close association with said base, so that it is substantially within the general outline of that end of said supporting stand, said handle member and said platform being adapted to be secured in a position such that said handle member overlies said crank member when said crank member is so folded adjacent to said support shaft, and adjustable brake means adapted to be caused to exert frictional pressure of selected amounts on said support shaft at will.

4. In a supporting stand for cameras and the like, having a longitudinally adjustable shaft adapted to carry a platform, brake means comprising a brake-shoe adapted to be moved at will into abutting relation to said shaft, an arcuate spring member abutting said brake-shoe at both

ends, and normally bowing out from said brake-shoe, an operating member having a reduced end portion adapted to extend through a central opening in said spring member and axially aligned with a recess in the face of said brake-shoe abutted by said spring member, and a shoulder on said operating member between said reduced end and the main body of said operating member, said shoulder being of greater diameter than said opening in said spring member and therefore being adapted to bear against said spring member when said reduced end is inserted through said opening, the length of said reduced end being greater than the depth of said recess so that said spring member may be compressed only a predetermined amount before said reduced end of said operating member abuts the base of said recess.

5. In a supporting stand for cameras and the like, having a longitudinally adjustable shaft adapted to carry a platform, brake means comprising a brake-shoe adapted to be moved at will into abutting relation to said shaft, a spring member abutting said brake-shoe, an operating member adapted to be moved to compress said spring member against said shoe, stop means carried by said operating member limiting its outward movement, a reduced end portion on said operating member axially aligned with and adapted to enter into a recess in the face of said shoe abutted by said spring member, the length of said reduced end being greater than the depth of said recess so that said reduced end will abut the base of said recess when said operating member is moved to compress said spring member a predetermined amount which amount is within the elastic limits of said spring.

6. In a supporting stand for cameras and the like, having a longitudinally adjustable shaft adapted to carry a platform, brake means comprising a brake-shoe adapted to be moved at will into abutting relation to said shaft, a coiled spring member abutting said brake-shoe, an operating member having a reduced end portion adapted to extend through said coiled spring and axially aligned with a recess in the face of said brake-shoe abutted by said coiled spring, the length of said reduced end being greater than the depth of said recess, a bushing carried by said reduced end of said operating member and abutting the outer end of said coiled spring, inward movement of said operating member causing said spring to be compressed, and said reduced end of said operating member to abut the base of said recess after said spring is compressed a predetermined amount which amount is within the elastic limits of said spring.

7. A supporting stand for cameras and the like comprising a base, a plurality of legs adapted to support said base, a support shaft mounted for sliding movement through an opening in said base, a platform on one end of said shaft, a longitudinal rack on said support shaft, a pinion shaft rotatably supported by said base, a pinion carried by said pinion shaft, said pinion and said pinion shaft being normally disposed so that said pinion engages said rack, a crank member pivotally connected to one end of said pinion shaft, means for locking the pivotal connection between said crank member and said pinion shaft at will so that said crank member becomes fixed with respect to said pinion shaft and when moved is adapted to rotate said pinion to cause said support shaft to move longitudinally with respect to said base, stop means establishing at least one

limit of longitudinal movement of said support shaft, said pinion and said rack being disengagable but capable of being reengaged so as to cause said crank member to return to a selected position of adjustment when said support shaft is moved so that said platform is brought into close relation to said base and further movement in that direction is prevented by said stop means, said selected position of adjustment of said crank member being such that when said locking means is released from said pivotal connection between said crank member and said pinion shaft, and said crank member is pivoted toward said support shaft, said crank member will be disposed in close association with said base and said platform so that it is disposed substantially within the general outline of that end of said supporting stand and adjustable brake means adapted to be caused to exert frictional pressure of selected amounts on said support shaft at will.

8. A supporting stand for cameras and the like comprising a base, a plurality of legs adapted to support said base, a support shaft mounted for sliding movement in said base, one end of said support shaft being adapted to support a platform, a longitudinal rack on said support shaft, a pinion carried by a pinion shaft journaled in said sleeve, said pinion being disposed to engage said rack, a crank member pivotally connected to one end of the pinion shaft, means for locking the pivotal connection between said crank member and said pinion shaft at will so that said crank member becomes fixed with respect to said pinion shaft and is adapted to rotate said pinion for causing said support shaft to move longitudinally with respect to said base, a brake member adapted to bear against said support shaft, means for urging said brake member toward said support shaft, and resilient compressible means interposed between said brake member and said second named means, so that pressure of finely selected amounts may be exerted on said support shaft by said brake member.

9. A supporting stand for cameras and the like comprising a base, a plurality of legs adapted to support said base, a support shaft mounted for sliding movement in said base, one end of said support shaft being adapted to support a platform, a longitudinal rack on said support shaft, a pinion carried by a pinion shaft journaled in said sleeve, said pinion being disposed to engage said rack, a crank member pivotally connected to one end of the pinion shaft, means for locking the pivotal connection between said crank member and said pinion shaft at will so that said crank member becomes fixed with respect to said pinion shaft and is adapted to rotate said pinion for causing said support shaft to move longitudinally with respect to said base, a brake member adapted to bear against said support shaft, means for urging said brake member toward said support shaft, and resilient compressible means interposed between said brake member and said first named means, said resilient means being sufficiently compressible to allow said first named means to move into abutment with said brake member when sufficient pressure is applied thereto by said first named means.

10. A supporting stand for cameras and the like comprising a base, a plurality of legs adapted to support said base, a support shaft mounted for sliding movement in said base, one end of said support shaft being adapted to support a platform, a longitudinal rack on said support shaft, a pinion carried by a pinion shaft journaled in

said base, said pinion being disposed to engage said rack, a crank member pivotally connected to one end of the pinion shaft, means for locking the pivotal connection between said crank member and said pinion shaft at will so that said crank member becomes fixed with respect to said pinion shaft and is adapted to rotate said pinion for causing said support shaft to move longitudinally with respect to said base, and a brake member having a concave surface thereon normally disposed adjacent the smooth, convex surface of said support shaft but adapted to be moved into abutment with said smooth surface of said support shaft at will and to apply adjustable amounts of pressure thereto.

11. A supporting stand for cameras and the like comprising a base, a plurality of legs adapted to support said base, a support shaft mounted for sliding movement through said base, one end of said support shaft being adapted to support a platform, a longitudinal rack on said support shaft, a pinion rotatably supported by said base in cooperative engagement with said rack, crank means for rotating said pinion to cause said support shaft to move longitudinally with respect to said base, a brake member having a concave surface thereon normally disposed adjacent the smooth, convex surface of said support shaft, means for moving the concave surface of said brake member into abutment with said smooth surface of said support shaft at will, and a resilient, compressible member interposed between said brake member and said last named means, so that pressure of finely selected amounts may be exerted on said support shaft by said brake member.

12. A supporting stand for cameras and the like comprising a base, a plurality of legs adapted to support said base, a support shaft mounted for sliding movement through said base, one end of said support shaft being adapted to support a platform, a longitudinal rack on said support shaft, a pinion rotatably supported by said base in cooperative engagement with said rack, crank means for rotating said pinion to cause said support shaft to move longitudinally with respect to said base, a brake member having a concave surface thereon normally disposed adjacent the smooth, convex surface of said support shaft, means for moving the concave surface of said brake member into abutment with said smooth surface of said support shaft at will, and a resilient, compressible member interposed between said brake member and said last named means, said resilient member being sufficiently compressible to allow said first named means to move into abutment with said brake member when sufficient pressure is applied thereto by said first named means.

13. A supporting stand for cameras and the like comprising a base, a plurality of legs adapted to support said base, a support shaft mounted for sliding movement through an opening in said base, a platform on one end of said support shaft, a longitudinal rack on said support shaft, a pinion shaft rotatably supported by said base, a pinion carried by said pinion shaft, said pinion and said pinion shaft being normally disposed so that said pinion engages said rack, a crank member pivotally connected to one end of said pinion shaft, means for locking the pivotal connection between said crank member and said pinion shaft at will so that said crank member becomes fixed with respect to said pinion shaft and when moved is adapted to rotate said pinion to cause said sup-

port shaft to move longitudinally with respect to said base, stop means establishing at least one limit of longitudinal movement of said support shaft, said pinion and said rack being disengageable but capable of being re-engaged so as to cause said crank member to return to a selected position of adjustment when said support shaft is moved so that said platform, is brought into close relation to said base and further movement in that direction is prevented by said stop means, said selected position of adjustment of said crank member being such that when said locking means is released from said pivotal connection between said crank member and said pinion shaft, and said crank member is pivoted toward said support shaft, said crank member will be disposed in close association with said base and said platform so that it is disposed substantially within the general outline of that end of said supporting stand, a brake member having a concave surface thereon normally disposed adjacent the smooth, convex surface of said support shaft but adapted to be moved into abutment with said smooth surface of said support shaft at will and to apply adjustable amounts of pressure thereto.

14. A supporting stand for cameras and the like comprising a base, a plurality of legs adapted to support said base, a support shaft mounted for sliding movement in said base, one end of said support shaft being adapted to support a platform, a longitudinal rack on said support shaft, a pinion shaft rotatably supported by said base, a pinion carried by said pinion shaft normally disposed in engagement with said rack, a crank member pivotally connected to said pinion

shaft, means for releasably locking the pivotal connection between said crank member and said pinion shaft at will so that said crank member becomes fixed with respect to said pinion shaft and said pinion may be rotated to thereby cause said support shaft to move longitudinally with respect to said base, said crank member and said pinion shaft being capable of being positioned so that said crank member may be pivoted toward said support shaft when said locking means is released and thus be disposed in close association with said base and said platform in unprotruding relation to and substantially within the general outline of that end of said supporting stand, and adjustable brake means adapted to be caused to exert frictional pressure of selected amounts on said shaft at will.

RAYMOND MOONEY.

Certificate of Correction

Patent No. 2,508,122

May 16, 1950

RAYMOND MOONEY

It is hereby certified that error appears in the printed specification of the above numbered patent requiring correction as follows:

Column 9, line 18, strike out the words "against longitudinal movement"; and that the said Letters Patent should be read as corrected above, so that the same may conform to the record of the case in the Patent Office.

Signed and sealed this 17th day of October, A. D. 1950.

[SEAL]

THOMAS F. MURPHY,
Assistant Commissioner of Patents.
